UNITED STATES PATENT OFFICE.

GEORGE E. MARLATT, OF PASADENA, CALIFORNIA.

TYPOGRAPHICAL ASSEMBLING AND DISTRIBUTING MACHINE.

Application filed October 5, 1926. Serial No. 139,721.

My invention relates to typographical machines of the kind in which circulating matrices are released from a magazine and assembled in line and then presented to a mold in which the printing type is cast against the line of matrices, the matrices subsequently being distributed to their individual channels in the magazine from which they were released.

Particularly, it relates to improved means for conducting the matrices into the magazine channels and releasing them therefrom, with the objects in view of rendering these operations more positive than heretofore and also simplifying the machine and increasing the capacity of the magazine without increasing its size. Heretofore the magazines of linotype machines have been made about one-third wider at their receiving end than the accumulative thickness of the stored matrices would actually require. The necessity for the excess width of the magazines at their receiving end has been due to the fact that the matrices in dropping from the distributing bar could not clear the lower distributor screw; therefore entrance partitions were provided equal in number to the magazine channels, the resultant channels between such partitions being of sufficient dimensions to receive the matrices following their interference with the lower distributor screw. It is the width of these partitioned entrance channels that has determined the width of the magazine at the receiving end, and this invention contemplates eliminating the entrance partitions and substituting therefor opposed-groove channels similar to those in the magazine and in continuation thereof. With such construction the magazines may be rectangular in shape instead of the usual trapezoidal form, and the channels therein may be parallel, thus greatly reducing the manufacturing cost of the magazine. Also, the matrices will more readily enter, travel through, and escape from the parallel channels than in the case of converging channels; the matrices will be distributed quicker by reason of the reduced width of the magazine at its receiving end, and additional channels may be added to the magazine without increasing its weight. Paralleling the channels of the magazine also renders feasible the form of matrix escapement of this disclosure, and this escapement in turn renders possible the simplification of the keyboard mechanism. An example of

the partitioned entrance above referred to as eliminated may be found in the patent to O. Mergenthaler, No. 436,532.

In the accompanying drawings:

Fig. 1 shows the usual trapeziform magazine overlying the rectangular form of magazine shown in connection with the principal figures of the drawings, and illustrates how the magazine may be widened at its lower end and narrowed at the receiving end in order to provide for additional channels without increasing its total area and weight.

Fig. 2 shows the usual trapeziform magazine between a rectangular magazine of less size but with an equal number of channels, and a rectangular magazine as wide as the trapeziform magazine at the receiving end but capable of containing one-third more channels than the usual trapeziform magazine.

Fig. 3 is a vertical section through the distributor, magazine and delivery throat of a linotype machine in which the matrices are delivered in vertical position to the entrance channels and thus necessitating a curved entrance channel. This view shows the application of my distributor improvements and a form of my improved escapement to a machine thus constructed.

Fig. 4 is a fragmentary section on the line 4—4 of Fig. 3.

Fig. 5 is a vertical section through part of a linotype machine, showing the application of my distributor and escapement improvements to a multiple-magazine linotype machine in which the matrices are delivered in a non-vertical position to distributing points and the usual curved entrance element is eliminated. Two forms of escapement, each differing somewhat from the showing of Fig. 3, are included in this view.

Fig. 6 is a side elevation of an improved keyboard and may be considered a continuation of Fig. 5.

Fig. 7 is a fragmentary perspective showing a series of escapements of the form illustrated in connection with the middle magazine of Fig. 5.

Fig. 8 is a vertical section through the discharge end of a magazine and the upper portion of the delivery throat, illustrating a modification of my improved escapement principle.

Fig. 9 is a sectional view showing the application of my distributor improvements to a form of linotype machine construction in

which the magazine entrance is pivoted at its upper end and at its lower end is movable from one to another of two magazines, selectively.

5 Fig. 10 is similar to the corresponding portion of Fig. 5 except that the distributor rail and the magazine are in extended alinement as distinguished from an angular relation of these parts as shown in Fig. 5.

10 Fig. 11 is a section through the discharge end of a magazine, showing a method of selecting between two sets of escapements on a magazine containing two fonts of matrices.

15 Fig. 12 is similar to Fig. 11, except that the operating reeds are shifted to engage a different set of escapements.

Fig. 13 shows the forward end of a magazine having escapement means similar to that illustrated in Figs. 11 and 12.

20 Fig. 14 is a view on the line 14—14 of Fig. 5.

Fig. 15 is a plan view of the keyboard and forward end of a magazine with the top plate omitted and showing the channels 25 therein.

Fig. 16 is similar to Fig. 15 but showing a keyboard with fewer keys and a corresponding number of magazine channels.

Fig. 17 is a continuation of Fig. 16 and 30 includes distributor-entrance channels to operate in common with the magazines of either Fig. 15 or Fig. 16.

35 Fig. 18 is a view of the left-hand side of the upper portion of Fig. 17, showing a device for preventing wrong-font matrices from entering the regular channels of the magazine.

Fig. 19 shows the keyboard of Fig. 6 in lowered and tilted position.

40 Referring to Figs. 3 and 4, the matrices X are as usual conveyed by means of the distributor screws 1, 2 and 3 along the distributor bar 4 until they reach a point above their individual channels. The omission of 45 a combination of ribs 5 on the bar 4 above any entrance channel indicates the retention of a corresponding combination of teeth on the matrices destined for such channel; therefore the matrices are released from the 50 rail when their retained combinations clear the ends of a combination of ribs on the bar.

55 As commonly constructed, the matrices have their screw-engaging lugs flush with their forward or lead side as they appear when traveling on the bar 4, and their distributing teeth flush with the opposite side, and since matrices of one font may exceed in thickness those of another font, I terminate the distributing combinations on the bar 4 with 60 reference to matrices of the thickest font; therefore matrices of thinner fonts will not immediately enter their channels when released from the bar 4, but will be supported by means of their upper lugs on rails 7 and 8 65 until they reach opposed grooves formed on

facing sides thereof, as more fully explained in my co-pending application Serial No. 546,383. With reference to the rails 7 and 8, this present invention is concerned principally with the angles of the grooves 7^a and 8^a 70 relative to each other and relative to the matrices while suspended from the distributor bar. It will be noted that the outer grooves 8^a are continuous with similar grooves 9^a in the magazine entrance 9 and that these 75 grooves 9^a are in continuation of the grooves 10^a in the magazine 10; but the inner grooves 7^a are of necessity interrupted by the lower distributor screw 3. The angle of the outer grooves 8^a relative to the suspended matrices 80 is such that the lower, outer lug, X¹ of the matrices will clear the ribs separating the grooves 8^a, while the matrices are being conveyed on the distributor bar 4; when the matrices reach their individual channels 85 their lower inner lugs X² immediately enter the inner grooves 9^a and both upper lugs X³, X⁴ enter the grooves 7^a, 8^a. The inner grooves 7^a are parallel with the opposite grooves 8^a but are of receding depth to avoid 90 interference with the horizontal travel of the matrices; hence both upper lugs on the matrices will remain in their channels except as the inner channel is interrupted by the lower distributor screw. A short distance 95 below the lower distributor screw the grooves 9^a in the magazine entrance channel approach each other, as at 9^a, therefore before the inner upper matrix lug X³ leaves its groove 7^a both lower matrix lugs will be 100 fully engaged in their channel 9^a and the lower distributor screw will prevent the upper outer lug X⁴ from leaving its channel. In order that the upper lug X³ of the 105 matrices may not enter the groove of the lower screw this screw is of reduced diameter with the result that the groove is made steeper than usual so that its vertical measurement is less than that of the matrix lug X³ and will be bridged by the lug when 110 passing the lower screw. (See Figs. 4 and 17.) It will be apparent that the channel angles as thus described and illustrated are such that only one matrix lug at a time may 115 remain out of engagement with its groove, and the simultaneous engagement of three lugs with their grooves will retain the matrix in such position that the disengaged lug will enter or re-enter its groove at the appropriate time. This arrangement makes possible the elimination of the usual magazine entrance partitions and a consequent reduction in the width of the magazine as explained in the preamble of this specification 120 and in the description of Figs. 1 and 2 of the drawings. Only a sufficient number of the partitions 9^c are retained to space apart the inner and outer channel plates of the magazine entrance 9. The outer grooved rail 8 125 is secured to suitable brackets 11 movable 130

with a shaft 12 mounted on the distributor beam 13 in order that the rail 8 may be moved outwardly and upwardly to provide access to the matrices or other parts. A 5 detent 14 serves to hold the rail in a selected position. The foregoing description of Fig. 3 also applies to Fig. 5 so far as similar reference numerals with different exponents are employed to designate corresponding parts. 10 But it will be noted that in Fig. 5 no magazine entrance channel is employed, and its elimination is made possible by the improvements above described in connection with the rails 7 and 8. In Fig. 5 the distributor bar 4^a is arranged at a greater angle than the magazine 10 in order that the initial drop of the matrices may be fast enough to cause them to enter the magazine without interfering with a following matrix. This 15 angle of the distributor bar may be more or less according to requirements, and in Fig. 10 it is shown centered in the same plane with the magazine.

The preceding description of Fig. 3 also 25 applies to Fig. 9, in which corresponding reference numerals with different exponents designate similar parts. But in Fig. 9 the grooves 7^c, 8^c, in the rails are curved to better co-operate with the grooves in the magazine entrance, which is pivoted at its upper 30 end and movable at its lower end from one to another of two magazines in manner similar to that disclosed in my U. S. Patent No. 1,266,970.

The principle of my improved matrix escapement resides in providing a pit or perforation adjacent the discharge end of each magazine channel, into which pit the forward or shorter lug of the matrices may 40 enter. A simple form of the escapement is shown in Fig. 3 in connection with a single-magazine type of machine. In this example the perforations take the form of notches 15 formed in series in the edge of the assembler 45 entrance throat 16. Each notch is occupied by the end of an escapement reed 17 and as the reeds are actuated in usual manner by manipulation of a keyboard, the lug X¹ of the matrix is raised out of engagement with 50 the notch 15 and the matrix is permitted to escape from the magazine, the following and longer lug X⁴ bridging the notch 15 instead of entering therein. The forward lug of the following matrix will then enter the 55 notch and be retarded until likewise released. By holding the reed 17 in raised position all or any number of the matrices in a channel may be caused to escape from the magazine, as when spacing or leadering out a line in 60 the assembler. In order that the ribs 18 which separate the channels 10^a of the magazine may not interfere with the body of thick matrices when retarded in the notches 15 these ribs are made of receding depth as 65 at 18^a between the lower and upper lugs of the

forward matrices in the magazine. For the single magazine type of machine a suitable locking bar 19 may be provided to prevent spillage of the matrices when the magazine is removed from the machine. A rod 20 may be changed from rear or front positions beneath side arms 21 mounted on a pivot rod 22 and carrying the locking bar 19. In Fig. 3 the rod 20 is shown in position to lock the matrices in the magazine, and in Fig. 8 it is shown in unlocking position.

Another simple adaptation of my escapement principle applicable to certain types of machines is shown in Fig. 8 and consists in dividing the assembler entrance throat into a series of pawls 23, one in front of each magazine channel. A centrally-pivoted lever 24 is associated with each pawl 23, and as the operating reeds 17^a are raised an associated pawl 23 is depressed from in front of a corresponding column of matrices and the forward matrix passes over the pawl to assembling position. The weight of the reed 17^a restores the pawl while the matrix is passing thereover and the following matrix is stopped as explained in the description of Fig. 3. A continuous plate 25 integral with the magazine provides a floor for the series of pits in which the forward lugs of the matrices rest.

In certain types or models of machines the magazines are arranged in a column as in Fig. 5, the column being movable in order to bring a selected magazine to operative position. For this type of machine I provide the escapement perforation 26 through each channel of the magazine. In connection with the upper and middle magazines of Fig. 5 the escapement reeds 17^b act directly upon the matrices. But where the channels of the magazines are crowded or arranged in pairs for accommodating two fonts of matrices I prefer to employ a thin escapement element 27 to be acted upon by the reeds 17^b. When the magazines contain two fonts of matrices (Figs. 13 and 14) the contact points 27^a of the escapement elements are placed fore and aft on alternate escapements, those having the forward position controlling one font of matrices and those having the rear position controlling the other font. By moving the operating ends of the escapement reeds from one to another of the two series of contact points 27^a a selected font of matrices is brought under control.

In order that both types of escapement shown in Fig. 5 may be employed in the same machine, I provide a keyboard (Figs. 6 and 19) which may be raised and lowered according to whether or not a magazine having the escapement elements 27 is in operative position, the reeds 17^b moving with the keyboard. At each of its ends the keyboard 29 is provided with studs 30 which rest on

straightline levers 31 pivotally connected to a slide supported on the stationary keyboard support 28. Links 33 are pivotally connected at their lower ends to the stationary frame 28 and at their upper ends to the levers 31. The slide 32 is provided with a rack, and is controlled by means of a gear 36 having an operating handle 37. When the keyboard is in raised position as in Fig. 6 a latch 38 holds the slide against forward movement, and when this latch is raised and the handle 37 moved rearwardly, the slide 32 moves forward, being supported by means of slide blocks 34 resting on a track 35. In its forward position the slide 32 is stopped by contact of the slide block 34 with a shoulder 39, and when in such position the upper ends of the supporting levers 31 will have been lowered and the keyboard correspondingly lowered to associate the reeds 17^b with the escapement elements 27^a when in operative position relative to the assembler entrance throat 16. When thus lowered the forward end of the keyboard rests on opposite cams 40 which are controlled by a handle 41 and serve to tilt the keyboard about the rear supporting points 30 for the purpose of placing the upper ends of the reeds 17^b beneath one or the other of the two series of contact points 27^a, selectively, according to the matrix font selected for use. When tilted as shown in dotted lines in Fig. 19 the reeds 17^c occupy the position shown in Fig. 11, the other position being shown in Fig. 12. The reeds 17^b are guided at their upper ends in a suitable perforated plate 42 and at their lower ends in a guide 43. These upper and lower guiding and spacing members are secured to side members 44 which are in turn held against the sides of the keyboard by means of latches 45 in a manner such as to permit the ready removal of the reeds 17^b from the keyboard for any purpose. Also, the keyboard as a whole may be readily lifted from position in the machine and a keyboard having a different number of keys substituted therefor, for use in connection with a magazine having a corresponding number of channels. In Fig. 15 is shown a keyboard having 120 keys and in Fig. 16 a keyboard having 78 keys.

Referring to Fig. 14, it will be noted that the contact points 27^a are bent alternately to the right or left according to series, so that the reeds 17^b may engage a selected series without any sidewise adjustment for that purpose. Instead of thus bending the escapement elements, the escapement reeds 69 may be split and forked as shown in Figs. 11, 12, and 13 with the tines of the forks offset in opposite directions from the body of the reeds. In Fig. 11 the reeds as thus formed are shown beneath one alternating series of escapements, and in Fig. 12 they

are shown beneath the other alternating series. With the reeds thus shaped the same result would be obtained if the two sets of escapements were of like shape.

Referring to Fig. 17, it will be noted that the distributor entrance rail 7^d is provided with notches 7^b equal in number to the channels of the magazine of Fig. 16, but has associated with it a magazine having a fewer number of channels. In order that both kinds of magazines may be employed in connection with a single type of rail 7^d, certain of the channels of the magazine having the lesser number of channels are bent at their upper ends as shown in Fig. 17 so that they are positioned to align in continuation of those channels 7^b of the rail 7^d which are intended to be operative in connection with a magazine having the fewer number of channels. It will be understood that such a magazine is intended to contain the larger sizes of matrices, and when the matrices are stored in the magazine in that portion thereof where the channels are parallel, no waste space need exist between the successive columns of matrices.

It is frequently necessary in the course of composition to employ special matrices or wrong-font matrices not intended to enter the storage channels of the magazine in use. Such characters are usually inserted by hand in the assembler (not shown) and after the casting operation are either removed by hand from the line prior to distribution, or, if notched for such purpose, are permitted to travel across the entire length of the distributor bar and enter a special receptacle beyond the magazine channels. In the latter case their font notch X^e must correspond in position with the similar notch of the font in use, otherwise the special or wrong-font matrices could not pass the usual font-distinguisher element, corresponding with the similar element A of Figs. 17 and 18 of this invention. In order that such special or wrong-font matrices may be automatically returned to the receptacle or channel in which they are kept, and this without necessitating their travel across the length of the distributor bar, I provide the font-distinguisher point A pivoted between the side plates 10^e of the magazine and in advance of the magazine channels. Matrices having the font notch X^e in regular position will clear the distinguisher point A and enter their magazine channels, but the special matrices having the font notch omitted, or wrong font, or matrices having their font notch differently positioned, will tilt the distinguisher point A about its pivot B, under the urge of the distributor screws. When this occurs a section 4^b of the distributor bar is raised into a clearance J and above the path of the distributing combinations X^f on the matrices. The matrix will therefore be dis-

engaged from the distributor bar 4^a and will drop into a spiral channel P and thence either through a tube N or an extra magazine channel O according to the position of 5 a switch element K, which may be controlled by means of a handle M on the outside of the magazine, the switch and handle being pivoted in common on a pivot shaft L. A lever C is pivoted in common with the distinguishing point A on the pivot shaft B and the two elements are joined together outside the magazine by means of a pin D for joint movement. The outer end of the lever C actuates an arm F which is connected by 15 means of a hinge pin G to a lever H carrying a link I from which is suspended the movable section 4^b of the distributor bar. A stop pin E serves to limit the return movement of the parts and thus locate the movable section 4^b in alignment with the main portion of the distributor bar 4^a. Through the connections as described, a wrong-font or special matrix will cause the movable section of distributor bar to be raised and the 20 matrix will enter the special channel P as explained. Any suitable receptacle or container may be employed at the termination of the tube N, and when occasion requires, as when repeatedly using a certain special matrix, it may be diverted into the magazine channel O and controlled for release by a special keyboard key or by manually lifting it out of the escapement perforations 26 of this invention.

35 Having described my invention, its construction and mode of operation, what I claim as new and desire to secure by Letters Patent of the United States, is:

1. In a typographical machine, in combination with a magazine having a series of channels in each of which matrices bearing a like character are stored in column arrangement for successive and intermittent release therefrom, and matrices therein having a short lug at their forward end and a relatively longer following lug on the same edge therewith, a perforation through the floor of each of said channels in which the short lug of each forward matrix in a 45 column lodges and thus hinders the escape of said matrices from their channel, and means for releasing said matrices one at a time from lodgement in said perforation, said means acting from beneath and through 50 said perforation to lift said matrix out of said perforation.

2. A combination and structure as set forth in claim 1 characterized by the fact that the means for lifting the matrices out 55 of the perforation therein recited is an escapement reed leading directly from a keyboard to and through said perforation.

3. A combination and structure as set forth in claim 1 characterized by the fact 65 that the means recited therein for lifting the

matrices out of engagement with said perforation is an escapement element carried by the magazine and actuated by an escapement reed leading from a keyboard thereto.

4. A combination and structure as set forth in claim 1 characterized by the fact that the channels therein recited recede in depth from a point adjacent the longer ear of the leading matrix in a column to a point adjacent said perforation, in order that the walls 70 between said channels will not prevent thick matrices from lodging in said perforation.

5. A combination and structure as specified in claim 1 characterized by the fact that the channels in the magazine therein recited are 80 formed in opposing upper and lower plates of said magazine and that the upper plate of said magazine terminates with such relation to the perforation in said lower plate that it will not interfere with the matrices 85 when lifted out of said perforation.

6. A combination and structure as specified in claim 1 characterized by the fact that the magazine therein recited is reversible end for end and side plate for side plate 90 when used with matrices having characters on both edges thereof, and that the perforations therein described are provided at both ends of said magazine but in opposite channel-plates thereof for selective use according 95 to the reversed and reversible positions of said magazine.

7. In a typographical machine, in combination with a magazine containing columns of matrices guided in opposed-groove channels for individual release therefrom and matrices having short forward lugs and long following lugs on each edge thereof for guiding said matrices in the opposed grooves of 100 said channels, a pit near the discharge end 105 of each of said channels into which the short lug of each successive matrix falls and remains pending its release therefrom.

8. In a typographical machine, in combination, matrices having short lugs on one 110 end thereof and long lugs on the other end thereof, a magazine having an individual channel for matrices bearing a correspondingly individual character, and a pit near 115 the discharge end of said channel into which a short lug of each successive matrix falls and remains until lifted therefrom.

9. In a typographical machine, in combination, a magazine having continuous channels therein in which matrices are stored 120 for release one at a time therefrom, matrices therein having short forward lugs and longer following lugs thereon, a delivery throat through which said matrices pass from said magazine, and means for releasing said matrices from said magazine, said means comprising a series of pawls serving as a part 125 of said throat adjacent said magazine, one pawl rising in front of each channel of said magazine and normally supporting the col- 130

- umn of matrices therein, the forward and short lug on said matrices dropping into an offset at the end of the magazine channels and resting against an associated pawl, and the longer and following lug on said matrices bridging said offset as the matrices pass from the magazine over said pawl following actuation of said pawl to free each successive matrix.
- 10 10. A combination as set forth in claim 9 including also the specified means for locking the matrices in their magazine when said magazine is to be removed from operative relation to said delivery throat.
- 15 11. In a typographical machine, in combination with a magazine having continuous and unbroken channels therein in which matrices having relatively short and long lugs are stored in columns, and a delivery throat 20 through which said matrices pass from said magazine, means for releasing said matrices one at a time from said magazine, said means comprising notches in the end of said delivery throat into which the short lugs of said 25 matrices enter from said magazine and from which they may be disengaged to permit the passage of the matrices through said delivery throat.
12. A combination and structure as specified in claim 11 including also means for preventing the escape of the matrices from said magazine when the magazine is moved from operative relation to said delivery throat, said means being a bar mounted 30 outside of said magazine and movable to a position in front of the columns of matrices in the magazine to prevent their escape therefrom, with means for locking said bar in operative or inoperative position selectively.
- 40 13. In a typographical machine, in combination with a magazine having two fonts of matrices therein arranged in alternating channels according to font and a series of escapements for releasing said matrices 45 from their channels, means for actuating alternate escapements selectively according to the font selected for use, said means including a series of reeds for actuating said escapements, said reeds having their ends 50 offset relative to opposite edges thereof and being movable fore and aft selectively in order that a selected edge of said series of reeds will engage only relative alternate escapements.
- 55 14. In a typographical machine, in combination with a magazine having two fonts of matrices therein arranged in alternating channels according to font and a series of escapements for releasing said matrices 60 from said channels, means for actuating alternate escapements selectively according to the font selected for use, said means including a series of reeds for actuating said escapements and said reeds being movable 65 in series in order to associate them with selected alternate escapements according to the font of matrices selected for use.
15. A combination as set forth in claim 14 characterized by the fact that the escapement-operating ends of the reeds therein recited vary in thickness according to the spacing of said escapements one from another.
16. A combination as set forth in claim 14 characterized by the fact that the escapements therein recited are variously spaced apart and are variously offset at their point of engagement with said operating reeds, in order to meet said reeds regardless of their spacing one from another and relative to the extent of sidewise movement of said operating reeds.
17. In a typographical machine, in combination with a magazine having two fonts of matrices therein disposed in alternating channels according to font, means for selecting one or the other of said fonts for release from said magazine, said means comprising two sets of escapements, one for each font of matrices, a single series of reeds 85 for actuating either of said sets of escapements, selectively, and a contact part on said escapements occupying different fore and aft positions relative in each set of escapements in order that said actuating 90 reeds may be moved from one to the other of said contact parts for actuating a selected set of escapements.
18. A combination as set forth in claim 17, including also a keyboard and characterized by the fact that the actuating reeds therein recited are movable with said keyboard in order to position their ends in operative relation to a selected set of escapements.
19. In a typographical machine, in combination, a set of magazines each having columns of matrices therein and escapements thereon for releasing said matrices, said magazines differing one from another as to the number of escapements thereon, according to the number of columns of matrices therein and individual keyboards for said magazines having escapement-operating reeds corresponding in number to the 100 escapements on associated magazines, including a structure permitting the removal of one keyboard and the substitution of another therefor according to the magazine selected for use.
20. In a typographical machine in combination, a magazine having columns of matrices therein disposed in alternating channels according to font, and a series of escapements for each font of matrices, said escapements alternating in shape according to the font of matrices with which they are associated in order that they may be actuated selectively according to the font of matrices selected for use.

21. In a typographical machine, in combination with magazines having matrices therein and escapements thereon for releasing said matrices, reeds for actuating said escapements and a keyboard for actuating said reeds, means for permitting said magazines to be moved to and from operative position without being obstructed by said reeds, said means consisting in lowering said reeds with said keyboard in order to position the escapement; operating ends of said reeds beyond the ends of said magazines while being moved to or from operative position.
22. A combination as set forth in claim 21 including also the specified means for lowering and raising said keyboard, said means comprising a pair of straightline levers at each end of said keyboard, one end of each of said levers serving to support said keyboard and having a vertical movement when said keyboard is raised or lowered, and the other end of each lever being pivoted to a horizontal slide for horizontal movement therewith on a stationary support, a link for supporting and spacing the outer end of said lever from said stationary support, and an operating handle geared to said slide for raising or lowering said keyboard and said escapement-operating reeds, with means for limiting the extent of movement of said keyboard and for latching it in its raised position.
23. A combination as set forth in claim 21 characterized by the fact that the escapements on said magazines may vary as to form between different magazines, one form of escapement being associated with the operating reeds when in raised position and the other form being associated therewith when in lowered position, and including means for associating said operating reeds with a selected series of that form of escapement involving the lowered position of said reeds, said means consisting in tilting said keyboard and said reeds in order to place the operating ends of the reeds beneath said escapements.

Signed at Pasadena, Los Angeles County, California, this 28th day of September, 1926.

GEORGE E. MARLATT.
